(57) **CLAIM**

The ornamental design for a locking device for removable clothes box, as shown and described.

DESCRIPTION

FIG. 1 is a perspective view thereof;

FIG. 2 is a front elevational view of a locking device for removable clothes box showing my new design;

FIG. 3 is a right side view thereof;

FIG. 4 is a left side view thereof;

FIG. 5 is a rear elevational view thereof;

FIG. 6 is a top plan view thereof; and,

FIG. 7 is a bottom plan view thereof.

The broken lines in the drawing depict portions of the locking device for removable clothes box that form no part of the claimed design.
